ADJUSTING MEANS

Royal F. Sickles, Springfield, and Herbert F. Oliver, West Springfield, Mass., assignors to F. W. Sickles Company, Springfield, Mass., a corporation of Massachusetts

Application May 19, 1936, Serial No. 80,608

7 Claims. (Cl. 151—30)

This invention relates to improvements in adjusting devices and is directed more particularly to means to facilitate the rigid securing of one member in various positions of adjustment with relation to other members.

The principal objects of the invention are directed to the provision of means to facilitate the adjustment of one part relative to another and this is accomplished according to the invention by novel means which is simple in form so as to be economical to manufacture and yet which is efficient in its operation.

The novel features of the invention are adapted for broad application but is particularly useful in connection with radio apparatus where it is customary to move one part into various positions of adjustment with respect to another and wherein said one part must be held against shifting from its adjusted position.

For purposes of explanation, it may be assumed that it is desired to move one member such as a coil relative to another coil and to lock the movable one in various positions of adjustment. In radio apparatus, the coils referred to may be extremely small in size and the increments of adjustment may be extremely small wherefore in order to obtain the desired adjustment, it is necessary to provide a device which permits very slight movements of the movable member. To overcome the possibility that said parts may be shifted or moved, the novel means of this invention efficiently and securely locks said movable part in position in a very efficient manner.

Various and numerous novel features and advantages of the invention will be hereinafter more fully referred to in connection with the accompanying description of the preferred form of the invention, reference being had to the accompanying drawing wherein:

Fig. 1 is a side elevational view of an apparatus embodying the novel features of the invention;

Fig. 2 is an enlarged plan view showing a lock washer member of the invention;

Fig. 3 is a transverse sectional view through the washer shown in Fig. 1; and

Fig. 4 is a fragmentary perspective view showing the central part of the washer shown in Figs. 1 and 2 to explain certain features of the invention.

Referring now to the drawing more in detail, the invention will be fully described.

As before stated, the invention is adapted for broad application. In order however to facilitate a clear understanding of the novel features there-

of it will be described in connection with a pair of coils 2 and 4, one of which it is desired to move or adjust relative to the other by the means now to be described.

The coil 4 is associated with a member 6 which extends from the support 8 and the coil 2 is movable towards and away from the said coil 4. A screw 10 is in screw-threaded engagement with the base or support 8 and its upper end is fixed to and carries the coil 2. The lower end of the screw 10 is provided with a slot 12 to receive a tool for rotating the same or of course said screw may be otherwise rotated in any well-known manner.

It will be appreciated that the screw-thread of the screw 10 and of the support 8 may be and ordinarily would be more or less loose to facilitate the free rotation of the screw 10. This looseness not only permits the screw to move relative to the support more or less but the lost motion is very objectionable when it is desired to obtain the fine adjustment necessary.

It is possible of course to use a lock nut on the screw for binding the screw to the support 8 but a lock nut must be turned up against the support. During the turning of the nut the screw is likely to be rotated more or less. This of course destroys the accuracy of the adjustment of the screw.

To yieldingly hold the screw against turning and therefore to lock the same and at the same time to eliminate any lost motion or looseness between the screw-threads of the screw and base, the novel washer 14 is provided. This washer is preferably of thin metal and it is curved or cupped as shown.

The washer is provided on its periphery with an inwardly extending slot or slots such as 16 of which there may be any desired number and an opening 18 is provided in the center of the washer for receiving the screw 10. This opening is of less diameter than the outside diameter of the screw. In fact the diameter of the opening corresponds rather closely to the root diameter of the screw at or near the bottom of its threads. A notch 20 leads outwardly from the said opening 18 and the parts 22 and 24 of the washer adjacent the opening 18 and the notch 20 are disposed in different planes. That is, the part 22 may be depressed while the part 24 is elevated slightly. It is desired that the parts 22 and 24 be offset or disposed in planes which are spaced from one another a distance substantially equal to the distance between adjacent threads of the screw.

screw while the peripheral edge 26 of the opening 18 of the washer between the part 22 and part 24 is spirally arranged to conform with the spiral formed by the thread of the screw.

- 5 As stated, the washer is of relatively thin metal and being provided with the slots 16, it is more or less spring-like so that the peripheral edge of the opening 18 thereof functions as a thread in the spiral groove of the screw.
- 10 In operation, the washer 14 is screwed onto the screw 10 while said screw 10 is screwed into the support 8. The washer 14 may be disposed on either side of the support 8 and when the washer 14 is adjacent the support 8 so as to bear thereon it is rotated. With reference to the drawing, it may be assumed that the thread of the screw 10 is a right-hand thread and in this case the washer is rotated in the direction of the arrow. The rotation may be accomplished by means of a tool 15 in engagement with a slot 16 thereof. This rotation of the washer relative to the screw causes the washer to be flattened out more or less so that it yieldingly bears on the base 8 or frictionally engages the same and exerts endwise 20 pressure against the screw.

The pressure of course may be varied according to the amount of rotation of the washer relative to the screw in abutment or engagement with the support. Of course the washer may be 30 varied in diameter, the length of the slots 16 may be varied and the thickness of the material of which the washer is made may be varied. These factors being all within relatively wide ranges facilitate various results.

35 With the washer thus rotated so that it bears on the support with a spring-like action and urging the screw axially, the screw is held against rotation and axial movements thereby so that any jarring will not cause the adjustment to be 40 changed and any looseness between the thread of the screw 10 and support 8 is eliminated.

When it is desired to adjust the screw it is rotated as may be desired but since the washer yieldingly bears on the support it resists rotation 45 and does not turn as the screw is turned. Therefore it is possible to adjust the screw up and down and at all times the screw is held by the washer against rotative and axial movements.

In an ordinary case where a screw is used for 50 adjustment there is likely to be such an amount of play in the threads that the screw will not remain in its adjusted position. In this case however the washer functions to hold the screw in its position of adjustment and in a way to be 55 distinguished from a lock nut. Where a lock nut is used and when the adjustment is made, the nut must be turned on the screw to bear against some part such as the support and in the turning of the nut to its final position, there is a tendency 60 to also turn the screw. In this case, however, the screw may be turned without any particular regard to the washer after it has been once brought under the proper tension and therefore it is an easy matter to rotate the screw to bring 65 about the extremely fine increments of adjustment which are desired in connection with radio apparatus and the like.

While we have described the invention in great detail and with respect to a preferred form 70 thereof, it is not desired to be limited thereto since many changes and modifications may be made therein without departing from the spirit and scope of the invention.

What it is desired to claim and secure by Letters Patent of the United States is;

1. As a new article of manufacture, a lock washer for yieldingly holding a screw comprising, a dished disc having a slot extending inwardly from the periphery thereof and a central opening, the said opening being of less diameter than the outside diameter of the screw with which said washer is to be used and having a spiral arrangement coinciding with the groove between the thread of the screw with which it is used. 5

2. As a new article of manufacture, a lock washer for yieldingly holding a screw comprising, a disk of relatively thin metal provided with a slot extending inwardly from its periphery and a central opening for a screw, the said disk inclining downwardly from its central part to its 15 periphery and provided with a notch in the periphery of said opening, the said opening being smaller in diameter than the outside diameter of the screw with which it is used and portions of the disk adjacent said notch at the periphery of 20 the opening being relatively offset in different planes the distance between which is equal to the space between the threads of the screw with which it is used and the periphery of said opening being disposed in a spiral to engage between 25 the thread of said screw.

3. The combination of a support and a screw 30 threadedly engaging the same with a lock washer for resisting rotating movements of said screw comprising, a disc-like member having an opening the periphery of which engages the groove between the thread of said screw, the said member being of spring-like thin metal provided with a slot in its periphery and being dished so that a surface thereof adjacent its periphery frictionally bears on said support and its central part is spaced therefrom, all adapted and arranged whereby said member yieldingly bears on said support to yieldingly urge said screw in one direction and resists but permits rotation thereof. 35

4. As a new article of manufacture, a washer for yieldingly holding comprising, a relatively thin normally flat disk-like body of flexible metal having a central part provided with an opening the periphery of which is arranged to threadedly engage a screw and a relatively flat peripheral portion, the said central portion and peripheral portions being disposed in different planes and the said peripheral portion being slotted to render the central and peripheral portion relatively 50 yieldable, all adapted and arranged so that as the washer is engaged with a screw which threadedly engages a member a relatively flat surface portion thereof adjacent an edge of said edge portion may frictionally engage a surface of the member to 55 exert yielding pressure axially of the screw whereby the washer resists rotation thereof by the screw and yieldingly resists rotation of the screw in either direction. 60

5. A washer device for a screw threadedly engaging and extending from a support comprising, a two-dimensional disc-like member of relatively thin spring-like metal which is dish-shaped having a peripheral portion and a central portion in different planes, the said central portion which is 65 dish-shaped being provided with an opening for threadedly engaging a screw and the peripheral portion being substantially smooth and slotted to render the said portion flexible and adapted to frictionally engage a support, all adapted and arranged whereby said member threadedly engaging a screw with its peripheral portion frictionally engaging a support may exert yielding pressure 70 axially of a screw to resist while permitting rotation thereof relative to a support but is rotatable 75

relative to the screw and support in either direction to vary the yieldable pressure exerted on said screw.

6. The combination of a support and a screw 5 threadedly engaging and extending therefrom with a device of the class described comprising, a two-dimensional disc-like member of relatively thin spring-like metal having a slotted peripheral portion and a central portion in different planes, 10 the central portion provided with an opening threadedly engaging the screw and having its peripheral portion relatively smooth and slotted to make said portion flexible and adapted to frictionally engage said support and exert yielding 15 pressure axially of the screw to resist while permitting rotation of said screw and being rotatable in either direction relative to said support and screw to vary the pressure exerted on the said screw whereby the screw may be rotatably 20 adjusted relative to the support whilst under yielding pressure.

7. The combination in radio apparatus of a support and a screw for a unit threadedly engaging and extending therefrom with a device of the class described comprising, a two-dimensional disc-like member of relatively thin spring-like metal which is dish-shaped having a slotted peripheral portion and a central portion in different planes, the central portion provided with an opening threadedly engaging the screw and having its peripheral portion relatively smooth and slotted to make said portion flexible and adapted to frictionally engage said support and exert yielding pressure axially of the screw to resist while permitting rotation of said screw and being rotatable in either direction relative to said support and screw to vary the pressure exerted on the said screw whereby the screw may be rotatably adjusted relative to the support whilst under yielding pressure. 5 10 15 20
